DESIGN FOR A DISPLAY CASING OR SIMILAR ARTICLE OF MANUFACTURE

Edwin A. Shank, New Rochelle, N. Y.

Application November 19, 1936, Serial No. 66,018

Term of patent 7 years

To all whom it may concern:

Be it known that I, Edwin A. Shank, a citizen of the United States of America and a resident of New Rochelle, county of Westchester, in the State of New York, have invented a new, original, and ornamental Design for a Display Casing or Similar Article of Manufacture, of which the following is a specification, reference being had to the accompanying drawing, forming a part thereof, in which

Fig. 1 is a front elevational view of a display casing, or similar article of manufacture illustrating my new design;

Fig. 2 is a top plan view thereof; and

Fig. 3 is a perspective view thereof on a reduced scale.

I claim:

The ornamental design for a display casing or similar article of manufacture, as shown.

EDWIN A. SHANK.
